C. E. NORDENDALE ET AL

GARMENT HANGER

Filed August 26, 1925

UNITED STATES PATENT OFFICE.

CHARLES E. NORDENDALE AND HARRY W. NORDENDALE, OF CHICAGO, ILLINOIS.

GARMENT HANGER.

Application filed August 26, 1925. Serial No. 52,632.

To all whom it may concern:

Be it known that we, CHARLES E. NORDENDALE and HARRY W. NORDENDALE, both citizens of the United States, residing at Chicago, in the county of Cook and State of Illinois, have jointly invented certain new and useful Improvements in a Garment Hanger, of which the following is a specification.

- 10 This invention relates, generally, to garment hangers or supporters, but has particular relation to a device to be used in homes, restaurants, hotels, and like places, as well as in or on automobile bodies, or the 15 bodies of other closed vehicles for supporting a garment or garments, such as a hat and coat worn by a lady or a gentleman.

The invention has for one of its objects, 20 the provision of a garment hanger, which shall be very simple and inexpensive in construction, strong, durable, and highly efficient in its operation, which may be employed for general use in supporting garments in a safe and secure manner, yet, so 25 that they will not be injured thereby, but may be quickly and readily removed for use.

Another object of our invention is, to provide a device in which both hat and coat, or 30 like garments, or either of them can be held thereby.

Still another object is, to provide a finger 35 hold by means of which the element for holding a hat can be readily moved for engagement with or release of the hat, and so that said hold or part will act as a safeguard in holding the coat-hanger, when used, safe and securely in position.

Numerous other objects and advantages 40 of our invention will become apparent from the following description and explanation.

The invention consists in certain peculiarities of the construction, novel arrangement, and combination of the various parts thereof, as will be hereinafter more fully set 45 forth and specifically claimed.

In the accompanying drawing, which serves to illustrate an embodiment of our invention,—

Fig. 1 is a face view of the completed device, showing its parts in position for supporting a hat and also a coat or like garment.

Fig. 2 is a side view in elevation of the device showing by dotted lines about the po-

sition a hat supported thereby will occupy, 55 the coat or like garment being omitted from the hanger therefor.

Fig. 3 is a greatly enlarged vertical central sectional view through the casing of the device, and illustrating fragments of the 60 hat holder and coat hanger in about the positions they will occupy when in use, and

Fig. 4 is a face view of a blank out of which the casing is formed.

Like numerals of reference refer to corresponding parts throughout the different views of the drawing.

The casing of the structure is indicated as a whole by the reference numeral 5, and is shown in Fig. 1 in its complete form, and 70 in Fig. 4 a blank, out of which the casing is made, is illustrated. Referring to this blank, 6 indicates the bottom of the casing, which is provided with a pair of spaced 75 openings 7 to register with a pair of spaced openings 8 formed in a portion 9 of the blank, which forms the face 9 of the casing when the part 10 is bent upwardly on the dotted line 11, and then horizontally on the dotted line 12. By bending the main portion 80 of the casing upwardly on the dotted lines 13 and 14, the sides thereof will be provided, each of which has an opening 15 as is evident. Fitted in the openings 15 is a small shaft 16 on which a coil spring 17 is 85 mounted and so constructed that one end 18 of said spring will rest against the bottom 6 while the other end 19 will rest against one of the prongs 20 of the hat holding ring 21, which may be of any suitable size and 90 material, but preferably of wire. The prongs 20 of the hat holding ring 21 are twisted together as shown at 22 and slightly bent outwardly from the wall on which the casing is secured as shown at 22 in Fig. 95 2 of the drawing. This arrangement provides a finger hold out of the part 22, by means of which the ring 21 can be turned on its pivot so as to allow the crown of the hat to be passed through said ring, and so 100 that the hat rim, which may be slightly upturned, will be received by the curved portion 22, thus offering no injury whatever to the hat or its rim. As shown in Fig. 3 of the drawing, the prongs 20 are provided at 105 their free ends with loops 23, which encircle the shaft 16 and that said prongs are spaced in parallelism as shown in Fig. 1

thereby allowing them to operate in guide-ways 24 formed by the narrow part 10 and the sides of the casing.

The casing is mounted upon an elongated plate 25 so that the fastening means 26 employed in the holes 7 and 8 will extend through suitable openings in the plate 25 into a wall 27 or other suitable support. This plate is considerably longer than the casing 5 and has at its lower end a pair of upturned spaced lugs 28 which lugs provide hook-like members for the support of a laterally elongated coat hanger 29 of the well known construction, which may be made of wire and 10 at its middle a pair of strands 30 extended at a right angle to the portion 29 and twisted together, as clearly shown in Figs. 2 and 3 of the drawing. The free ends of the strands 30 of the coat hanger are bent in opposite 15 directions to each other, thereby affording arms 31 to rest against the upper surface of the hooks 28 in such a way that the strands 30 will depend from said lugs.

It will be observed by reference to Figs. 25 1 and 2 of the drawings that the curved portion 22 of the shank of the hat ring 21 is located so that its upper end will lie, when the hat ring 21 is in the position shown in Fig. 2, slightly above and between the intermediate space provided between lugs or 30 hooks 28 and will thus securely prevent the strands 30 and arms 31 of the coat hook being accidentally displaced.

Having thus fully described our invention, what we claim as new and desire to secure by Letters Patent is:—

1. In a device of the class described, the combination with a plate and a casing secured to one end thereof, of upwardly extended spaced lugs at the other end of said plate, said end of the plate adjacent said casing, and said casing secured to a support, said casing having a pair of spaced guide-ways between its sides, a hat holding ring

having strands twisted together and extended radially therefrom, the said strands being separated near their free ends and pivotally connected to the interior of the casing so as to operate in said guide-ways, a coil spring mounted transversely in said casing and having one of its ends in contact with one of said strands and its other end in engagement with said casing, a coat hanger having extended therefrom at about its middle, a shank provided at its free ends with arms to engage said lugs, the said strands of the hat ring being adapted to normally rest slightly above and between said lugs. 45

2. In a device of the class described, the combination with a plate and a casing secured to one end thereof, of upwardly extended spaced lugs at the other end of said plate, the end of the plate adjacent said casing and said casing secured to a support, said casing having a pair of spaced guide-ways 50 between its sides, a hat holding ring having strands twisted together and extended radially therefrom, the said twisted portion of said strands being curved outwardly from said support and separated near their free 55 ends and pivotally connected to the interior of the casing so as to operate in said guide-ways, a coil spring mounted transversely in said casing and having one of its ends in contact with one of said strands and its other 60 end in engagement with said casing, a coat hanger having extended therefrom at about its middle a shank provided at its free end with oppositely extended arms to engage 65 said lugs, the said curved portion of the 70 strands of the hat ring being located to normally rest slightly above and between the lugs and to afford a finger hold for releasing the ring and means for preventing an 75 upturned hat rim from being marred or injured. 80

CHARLES E. NORDENDALE.
